UNITED STATES PATENT OFFICE.

WILLIAM FIELDS, OF WILMINGTON, DELAWARE.

SMELTING-FURNACE.

SPECIFICATION forming part of Letters Patent No. 227,510, dated May 11, 1880.

Application filed January 17, 1880.

To all whom it may concern:

Be it known that I, WILLIAM FIELDS, a citizen of the United States, residing at Wilmington, in the county of New Castle and State 5 of Delaware, have invented certain new and useful Improvements in Furnaces; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

This invention relates to hydrocarbon-furnaces for smelting gold, silver, copper, lead, and zinc ores.

The invention consists in a furnace embodying a removable receptacle for burning crude petroleum or other hydrocarbon, an improved 20 draft-stack, a blast, a well for receiving the melted ore and separating the metal and slag, and dampers for regulating and controlling the draft, as hereinafter specified and claimed.

In the drawings illustrating my invention, 25 in the several figures of which corresponding parts are similarly designated, Figure 1 is a perspective view; Fig. 2, a vertical longitudinal section; Fig. 3, a horizontal cross-section on line xx of Fig. 2; Fig. 4, a perspective 30 view of the hydrocarbon-receptacle, partly broken to show its internal shape; and Fig. 5, a partly-sectional perspective of a portion of the stack and means for collecting and saving the fine particles of metal that may be forced 35 into the stack.

A designates a brick or other hearth having a well, B, which, as will hereinafter appear, is designed to receive the smelted ore and separate the slag and metal, the former being drawn 40 off at the mouth C and the latter at the mouth D. E is a duct leading from the hearth proper, L, to the well B.

F is a chamber arranged above the hearth, and having a door, G, and a register or damper, H, in said door. This chamber F is designed 45 to receive through its door a fire-brick or equivalent refractory vessel, I. This vessel is an annular trough, the trough proper, K, being formed between two annular walls, the inner 50 wall making a central orifice, M. This vessel I is designed to receive crude petroleum or

other hydrocarbon, which may be ignited by the blaze from the live coals in hearth L, and is constructed with the inner wall lower than the outer wall, to compel any overflow of petroleum that may possibly occur to fall on the hearth, thus preventing its passage to the outside through the door G. Said ring has also a suitable means of communication from outside the chamber, as shown in Fig. 2. 55

N is the furnace proper, in which the ore to be smelted is properly placed—viz., a layer of fuel and a layer of ore, and so on, until filled. This furnace has a water-space, O, surrounding it, and is lined with fire-brick or other 60 suitable refractory material, P. From the lower part of the furnace a flange, h, extends inward to the edge of the orifice M. Q Q' are doors provided at the top and bottom, respectively, of the furnace for ready access to its interior, 65 the lower door being specially valuable in permitting access to a part of the furnace requiring most frequent repairs. The furnace is crowned with a dome, R, terminating in a short stack, S. Exterior to this stack is the ordinary 70 stack T, and this latter is provided at its base with air-inlets a, regulated by a sliding covering-ring, e.

As the furnace is heated up, the ascending 75 column of heated products of combustion through the stack S creates a draft in the stack, whereby the external air is drawn in, and becoming heated rises rapidly, drawing the gases from below through the short stack and intensifies the draft in the furnace. The 80 stack T may have the ordinary damper T', Fig. 5, for controlling the draft. The water-jacket O has an inlet, c, and an outlet, d. The well B may have a removable cover, B'.

Blast-pipes or tuyeres e e' may be arranged 85 above and below (either or both) the oil-receptacle I.

In smelting ores with the blast, fine particles of metal are blown up the stack and so lost. In order to prevent this I insert a goose-neck, 90 V, in the stack and flare out its inner end, as at W, so as to nearly fill the stack. This goose-neck extends thence to receiver U, whereby these fine particles are collected and saved.

The draft over the hydrocarbon may be regulated by the damper or register H in the door 95 G, and by means of this door the said vessel

may be readily removed, renewed, or replaced while the furnace is even at white heat.

The operation is as follows: The furnace having been filled with alternate layers of fuel and ore, the lower layer being of charcoal, the fire is kindled in the hearth L, the hydrocarbon in the vessel I ignited, and the blow begun. As the metal melts it flows down with the slag through an opening in the bottom of the furnace that registers with the opening M of the receptacle I, and thence through the duct E into the well B, where it and the accompanying slag are separated, as before described.

The use of a hydrocarbon prevents a low or chill of the smelted ores and greatly facilitates the operation of smelting.

By my invention I get the combined heat of the gases of hydrogen and oxygen and carbon, and thus obtain a very intense heat.

20 What I claim is—

1. The combination of a furnace, N, a hydrocarbon-burning chamber intermediate of the

furnace and its hearth, a hearth, and a separating-well, substantially as described.

2. In a smelting-furnace, a chamber, F, intermediate of the furnace and its hearth, substantially as and for the purpose described. 25

3. The combination, with a smelting-furnace, of a trough-like refractory receptacle for hydrocarbons, having the inner wall lower than the 30 outer wall, substantially as described.

4. A smelting-furnace crowned with a dome terminating in a short stack, S, surmounted by an exterior stack, T, provided at its base with air-inlets for inducing an increased draft 35 by introducing air to mingle with the products of combustion, substantially as set forth.

In testimony whereof I affix my signature in presence of two witnesses.

WILLIAM FIELDS.
